(57) **CLAIM**

The design for a dust cup for vacuum cleaner, as shown and described.

DESCRIPTION

FIG. 1 is a dust cup for vacuum cleaner showing our new design on a stick-type vacuum cleaner;
FIG. 2 is an enlarged perspective view of the dust cup alone;
FIG. 3 is a front elevational view thereof;
FIG. 4 is a rear elevational view thereof;
FIG. 5 is a left side elevational view thereof;
FIG. 6 is a right side elevational view thereof;
FIG. 7 is a top plan view thereof;
FIG. 8 is a bottom plan view thereof; and,
FIG. 9 is an exploded perspective view thereof.
The components illustrated in broken lines in FIGS. 1 and 9 form no part of the claimed design.
